CAPTIVE GLIDERS

Camille Florent Dauwe, Ghent, Belgium

Application September 9, 1953, Serial No. 379,232

Claims priority, application Belgium September 17, 1952

7 Claims. (Cl. 46—77)

The present invention relates to a captive glider, serving mainly as a toy, capable of effecting sustained flights of unlimited duration, and kept in flight by successive pulls, communicated to it by a string or cord, operated for example, by a hand reel according to my copending patent application Serial No. 374,361 filed August 14, 1953 for a Reel for Flying Toys. Each pull is followed by a relaxing of the tension in the cord, which permits the glider to return back to its point of departure after banking and turning to left or to right, according to the will of the operator, this banking in the desired direction being accompanied by a decrease of speed for one direction of turning and an increase of speed for the opposite direction, the different wing lift pressures resulting from the different speeds causing variation of the effective angle of attack of a movable flap portion of one of the wings, to such an extent that, during deceleration, it becomes sufficiently higher than the level of the opposite relatively fixed wing to produce a bank and turn towards the latter, whilst during acceleration it becomes sufficiently lower to produce a bank and turn in the opposite direction. To this end almost the entirety of one of the wings is constituted by a flap portion capable of effecting small movements of rotation about a pivotal axis obliquely inclined with respect to the longitudinal axis of the glider fuselage at an angle open towards the front. This pivotal axis $X'-X$ lies in a vertical plane which recesses the longitudinal axis of the fuselage at a point located rearwardly of the leading edges of the wings.

Various other objects, features and advantages of the invention will appear upon reading the following together with the accompanying drawing forming a part hereof.

Referring to the drawing:

Figure 1 is a plan view of a glider embodying the invention.

Figure 2 is a side view in elevation of the embodiment shown in Fig. 1.

Figure 3 is a front end view showing a movable flap portion of one of the wings depressed to its lowermost position for banking the glider in a left turn.

Fig. 4 is a view similar to Fig. 3 showing the movable flap portion raised for banking the glider in a right turn.

Figure 5 is a rear perspective view of the forward portion of the fuselage.

Figure 6 is a rear perspective view of the rear portion of the fuselage.

Figure 7 is a front elevational view showing the wings detached from the fuselage.

Figure 8 is a perspective view showing the wings in a folded position for enclosure in a package with other parts of the glider when the glider is not in use.

Figure 9 is an enlarged perspective view of a spring used for depressing the movable flap portion of one of the wings.

Figure 10 is an enlarged fragmentary perspective view showing the spring of Fig. 9 assembled in a flexible joint

which connects the flap portion to the fixed portion of one of the wings.

Figure 11 is a perspective view showing the tail structure detached from the fuselage and in a folded condition for compact packaging of the glider parts.

Figure 12 is a perspective view showing the skeleton of one of the wings.

The captive glider comprises an assembly of four separable units: two rod members which may be assembled endwise to form an elongated fuselage, a pair of wings, and a tail structure consisting of a rudder and elevators hingedly connected together.

The rods 1 (Figs. 1 and 5) and 2 (Figs. 1 and 6) can fit in one another owing to a socket 3 (Fig. 5); the wings are connected together by a flexible joint 4 (Figs. 3, 7 and 8) permitting them to be folded back (Fig. 8), and leaving between them an opening 5 (Fig. 7) into which the fuselage can be introduced and fixed by the pressure of two lugs 6 (Figs. 3 and 7), which pressure results from the adjustable tension of a stay 7 (Figs. 1, 3 and 4). The tension of the stay is adjustable owing to the fact that one of its ends is fixed to the end of a wing, and the other is fixed to a loop 8 (Figs. 1 and 2) encircling the other wing and capable of being displaced along the latter in the direction of its length.

One of the wings is formed almost entirely by a flap 9 (Figs. 1 and 3) capable of small angular movements about an axis $x-x'$ (Fig. 1), forming with the longitudinal axis of the glider an angle α open towards the front. These angular movements are rendered possible by the fact that the flap is connected to the small fixed part 10 (Figs. 1, 8 and 10) of the wing by a flexible joint 11 (Figs. 8 and 10). The said movements enable the flap to take up positions such that its incidence can be greater (Fig. 3) or less (Fig. 4) than that of the opposite wing. A spring 12 (Figs. 8 and 10) in the form of an open delta (Fig. 9) fixed in the joint presses the flap downwardly; it always has an excess of power over that required for maximum operation. The stay 7 (Figs. 1, 3 and 4) draws the flap upwardly and by its well regulated tension determines the necessary position of the flap.

An elastic 13 (Figs. 3 and 4) is fixed at its two ends to the stay 7 by means of two small sleeves 14 and 15 (same figures); these, formed by a series of very tight knots, can slide along the stay with sufficiently strong friction to remain in place at any part of the stay and whatever be the tension of the elastic. Spring 12 tends to depress flap portion 9 against the yielding tension of an elastic 13, this downward movement being limited by the relatively unyielding cord or stay 7 when the portion of the stay 7 included between the sleeves 14 and 15 becomes taut as shown in Fig. 3. When the upward air pressure on flap portion 9 increases during flight by pulling on a manipulating string 30, this forces the flap portion 9 upwardly against the action of spring 12, this upward movement being aided by elastic 13 to an extent determined by the spacing between the sleeves 14 and 15 and the portion of the stay 7 included between sleeves 14 and 15 slackens into a loop as shown in Fig. 4.

The tail structure (Fig. 11) comprises a rudder member 16 having a curved lower forward edge portion 17. As described below, curved edge portion 17 serves for adjusting the angle of attack of elevator member 18 which is hingedly connected intermediate its ends to rudder member 16 by a flexible joint 19. Secured to the projecting end portions of elevator member 18 is a loop or length of string 20 which may be passed over the inclined serrated upper edge 21 (Figs. 1 to 4) of rudder member 16 to hold the rudder member 16 erect with respect to the elevator member 18 by frictional engage-

ment between the string 20 and one of the notches of the serrated rudder edge 21. The tension in string 20 and its frictional engagement with serrated edge 21 may be readily increased by moving string 20 to pass through a more rearwardly disposed notch in the upwardly inclined serrated edge 21 of rudder 16. As shown in Figs. 1 and 2, an endless elastic band 22 has its end portions looped around the left side of rear fuselage member 2 at the rear thereof and between its looped end portions, the elastic band 22 engages the right hand side of rudder member 16 pressing it laterally into frictional engagement with the right hand side of rear fuselage member 2. By adjusting the points of contact between the forward loop of elastic band 22 and the curbed forward edge portion 17 of rudder member 16, the angle of attack of elevator member 18 may be adjusted before flight to provide the desired rate of climb as the glider is pulled forwardly by the manipulating string 30 connected to the fuselage 1, 2.

The ribs of the wings and of the height stabilizer consist of two parts 23 and 24 (Fig. 12) glued against the single longitudinal 25; the edges of the wings are formed by a thread 26 (Fig. 12) fixed along the ends of the ribs 23, 24 by bending back and gluing the edge 27 of the lower membrane. All the parts which constitute the captive glider, after taking apart and folding up may be introduced into a box whose two greatest dimensions are little more than that of a single wing.

The adjustment and operation are as follows:

Before launching the flap is given an incidence greater than that of the opposite wing (Fig. 3), by adjustment of the tension of the stay; the elastic is given a tension such that after the necessary raising of the wing (Fig. 4) the stay keeps at its end a tension which equals and balances the excessive tension of the spring. The glider will now veer in the direction of the flap on acceleration, owing to the increase of air pressure which raises the flap and reduces its incidence, and to the opposite side on retardation, due to the reduction of air pressure, which permits the flap to recover and resume its greater incidence.

What I claim is:

1. A glider of the class described, comprising: an elongated fuselage; a tail structure at the rear of said fuselage; a pair of wings connected to said fuselage forwardly of said tail structure and extending laterally outwardly from said fuselage, one of said wings being effectively rigid during flight and having a fixed angle of attack; pivot means included in the other of said wings intermediate said fuselage and the outer end of said other wing, said pivot means causing said other wing to incline an outwardly disposed flap portion movable about a pivotal axis which is oblique with respect to the longitudinal axis of said fuselage for changing the effective angle of attack of said other wing in response to pivotal movement of said flap portion; resilient means acting on said flap portion and yieldingly urging said flap portion downwardly to change the effective angle of attack of said other wing with respect to said one wing and bank said glider in a turn in a predetermined direction; and

a manipulating string connected to said fuselage for pulling said fuselage through the air and increasing the air pressure beneath said flap portion, for urging said flap portion upwardly against the yielding action of said resilient means to change the effective angle of attack of said other wing in the direction opposite to said first-named change and bank said glider in a turn directed oppositely to said predetermined direction.

2. A glider according to claim 1, wherein said pivotal axis lies in a vertical plane which crosses the longitudinal axis of said fuselage rearwardly of the leading edges of the wings.

3. A glider according to claim 1, further comprising a second resilient means acting on said flap portion and yielding urging said flap portion upwardly against the action of said first-named resilient means; and means connected to one of said resilient means for adjusting the relative actions of said two resilient means for determining the amount of response of said flap portion to variations in air pressure thereon during flight.

4. A glider according to claim 1, further comprising limiting means connected to said flap portion and limiting said downward movement thereof.

5. A glider according to claim 4, in which said wings are inclined upwardly and outwardly from said fuselage and wherein said limiting means comprises a stay cord extending between outwardly disposed portions of said one wing and said flap portion of said other wing, one end of said stay cord comprising a noose encircling said one wing for adjustment therealong to vary the lowermost position of said flap portion.

6. A glider according to claim 5, further comprising an elastic tension member having its ends connected between spaced points on said stay cord intermediate the ends of said cord for yieldingly maintaining a tensile force acting between the ends of said cord and urging said flap portion upwardly against the action of said first-named resilient means.

7. A glider according to claim 6, wherein at least one end of said elastic tension member is connected to said stay cord by securing means adjustably movable along said cord for varying the amount of said tensile force acting between said ends of said cord.
